MOVABLE SHELF SUPPORTING STRUCTURE
FOR OVENSAnton K. Weiskittel, Baltimore, Md., assignor to
Harry C. Weiskittel Co. Inc., Baltimore, Md., a
corporation of Maryland

Application August 23, 1937, Serial No. 160,546

6 Claims. (Cl. 126—340)

My invention relates to stove constructions, and more particularly to a movable shelf supporting structure for ovens.

It is an object of my invention to provide a movable shelf supporting structure for ovens which is simple in construction and strong and durable in operation.

Another object of the invention is to provide a shelf supporting structure for ovens which will tend to maintain either its forward or back position after it has once reached the end of its travel in either forward or backward direction.

A further object of my invention is to provide a construction which is light and positive in action and easy to repair and replace.

With these and other objects in view, which may be incident to my improvements, the invention consists in the parts and combinations to be hereinafter set forth and claimed, with the understanding that the several necessary elements comprising my invention may be varied in construction, proportions and arrangements, without departing from the spirit and scope of the appended claims.

In order to make my invention more clearly understood, I have shown in the accompanying drawings means for carrying the same into practical effect without limiting the improvements in their useful applications to the particular constructions which, for the purpose of explanation, have been made the subject of illustration.

In the drawings:

Figure 1 is a perspective view of my stove construction embodying my oven, with the oven door closed;

Figure 2 is a view similar to Figure 1, with the pull out structure in the out position;

Figure 3 is a view in side elevation of my pull out construction in which parts have been moved to clearly show the operation;

Figure 4 is a view taken on the line 4—4 of Figure 3, looking in the direction of the arrows;

Figure 5 is a sectional view taken along the line 5—5 of Figure 6, looking in the direction of the arrows;

Figure 6 is a sectional view taken along the line 6—6 of Figure 5, looking in the direction of the arrows;

Figure 7 is a schematic view showing the position of the various parts during the opening and closing of the oven door.

Referring to the drawings I have shown a stove having a pull out shelf supporting construction which I have designated generally by the number 2. This pull out shelf supporting con-

struction comprises a vertical door 3, which is pivoted at 4 (see Figure 6) to the oven, and is provided with a handle 5 near the top.

The oven construction proper comprises an oven space 6 which has an insulated back wall 5 and an insulated top wall 8. The door 3 is insulated as indicated at 9. There is also provided an insulated side wall 10. The interior side wall is insulated for a portion of its length, as indicated at 11.

There is a shelf carrying, movable support 12 positioned in the oven, and a burner construction 13 which is adapted to heat a roasting shelf 14 which is attached to the shelf carrying, movable support 12 at the bottom.

The roasting shelf 14 comprises support brackets 15 on either side of the shelf which are attached by means of bolts 16 to support racks 17 on either side of the movable support 12. The supports 15 are formed with stops 18 which are adapted to lie against stops 19 formed just above the oven door 3 in its lowermost position (see Figure 3). The stop 19 is provided with a flange 20 against which the support brackets 15 rest.

In the rear position of the shelf carrying, movable support, which is formed of the members 17 and the roasting shelf 14, the rear of the members 15 is adapted to rest on a shelf 21 attached to the inner wall of the rear insulated wall 7 of the oven.

The members 17 are provided with trackways 22 in which are adapted to slide movable shelves 23 which can be slid for instance in the rear position, see top shelf of Figure 3, or left into the forward position, see bottom shelf 23 of Figure 2, when the oven door is opened. The burner 13 is adapted to heat the roasting shelf 14.

The shelf carrying, movable support 12 is carried by support arms 24 pivoted at points 25 on either side of the oven. The support arms 24 are pivoted at their upper ends, as indicated at 26, to the members 17 which form the shelf carrying, movable support 12. The door 3 has attached to it at either side operating arms 27 which are curved rearwardly, as indicated in Figure 3, or downwardly, as indicated in Figure 6, when the oven door is shut.

These short operating arms 27 are provided with an attaching plate 28, which is affixed to the interior of the door 3. At the ends 29 of the operating arms 27 are pivots 30 to which are attached links 31 on either side of the oven. The links 31 are pivoted at 32 to the forwardly located support arms 24 (see Figure 6). A spring member 33, which is attached at 34 to a support 35

35 within the oven 6, is also attached at its upper end 36 to one of the links 31.

The plurality of links 31 and the plurality of operating arms provide a strong construction 5 which does not make it necessary for a linking together of the support arms 24 on either side of the oven at their lower ends, as has heretofore been, in general, necessary.

It is to be noted that the pivot 30 which connects the operating arms 27 and the links 31 is close to the hinge 4 for the front door of the oven. This construction throws a minimum of strain on the front door and also does away with long sections of linkage and support mechanism.

15 The simplicity of the construction is readily apparent from the open position of the oven, as illustrated in the perspective view of Figure 2. The spring 33, by reason of its downward pull on the links 31, and the arms 27 tend to hold the oven door closed, thereby simplifying the construction of the door hinges 4. The shelf carrying, movable support 12 will be securely maintained in either its extended or retracted position by reason of the fact that its weight is carried by the arms 24 which swing either forward 20 or behind their pivot points 25. The spring 33 will also assist in maintaining the shelf carrying member 12 in either of its positions.

25 The positions of the parts in opening and shutting of the door are readily apparent from the diagrammatic showing in Figure 7.

30 While I have shown and described the preferred embodiment of my invention, I wish it to be understood that I do not confine myself to the 35 precise details of construction herein set forth by way of illustration, as it is apparent that many changes and variations may be made therein, by those skilled in the art, without departing from the spirit of the invention, or exceeding the 40 scope of the appended claims.

I claim:

1. In an oven construction, a door for the front of the oven, a pivot for the door, a slideable shelf carrying support, link means to move the support, 45 an operating arm pivoted to the link means at one end and attached to the door at the other end, said point of pivoting of link and operating arm lying close to the pivot for the door, and a spring attached to the operating link tending to hold the movable support in either the front or back position.

2. In an oven construction, a door for the front of the oven, a pivot for the door, a slideable shelf carrying support, link means to move the support, 50 a backwardly curved operating arm pivoted to the link means at one end and attached to the door at the other end, said point of pivoting of link and operating arm lying close to the pivot for the door.

the door, and a spring attached to the operating link tending to hold the movable support in either the front or back position.

3. In an oven construction, a shelf carrying movable support, support arms pivoted near the bottom of the oven, pivot connections near the top of the movable support for the support arms, a door, a pivot for the door, link means to move the support, and backwardly curved operating arm pivoted to the link means at one end and attached to the door at the other end, said point of pivoting of link and operating arm lying close to the pivot for the door, said support arms in their forward position lying within the oven.

4. An oven construction comprising an oven, 15 a shelf carrying movable support therein, support arms pivoted near the bottom of the oven, pivot connections near the top of the movable support for the support arms, a door, means attached to the door adjacent the bottom thereof and to one of said support arms to cause the movable support to move forward when the door is opened, a roasting shelf carried by the movable support, a stop at the front of the oven contacting with the roasting shelf to stop the forward movement of the movable support, and a stop in the oven at the rear against which the roasting shelf contacts at its rearmost position.

5. An oven construction comprising an oven, 20 a shelf carrying movable support therein, support arms pivoted near the bottom of the oven, pivot connections near the top of the movable support for the support arms, a door, a backwardly curved operating arm secured at one end to the door adjacent the bottom thereof and attached to one of the support arms at the other end to cause the movable support to move forward when the door is opened, a roasting shelf carried by the movable support, a stop at the front of the oven contacting with the roasting 25 shelf to stop the forward movement of the movable support and a stop in the oven at the rear against which the roasting shelf contacts at its rearmost position.

6. An oven construction comprising an oven, 30 a shelf carrying movable support therein, arms pivoted near the bottom of the oven, pivot connections near the top of the movable support for the arms, a door, a pivot for the door, a link pivoted at one end to one of said arms, a backwardly curved operating arm attached at one end 35 near the bottom of the oven door and pivoted at the opposite end to said link, the pivot point of the link and the operating arm lying adjacent the pivot for the door, and a spring attached to the operating link tending to hold the movable support in either the front or back position.

ANTON K. WEISKITTEL.
